[57] CLAIM

The ornamental design for a hologram display, as shown and described.

DESCRIPTION

FIG. 1 is a front elevational view of a hologram display embodying my design;

FIG. 2 is a left side elevational view thereof, the right side being a mirror image thereof;

FIG. 3 is a top plan view of the hologram display as shown in FIG. 1, the bottom plan view being a mirror image thereof; and,

FIG. 4 is a rear elevational view thereof.
